DESIGN FOR A SYMBOL TEMPLATE

Robert W. Anderson, Weehawken, N. J., assignor to Keuffel & Esser Company, Hoboken, N. J., a corporation of New Jersey

Application February 7, 1945, Serial No. 117,810

Term of patent 14 years

(Cl. D52—1)

To all whom it may concern:

Be it known that I, Robert W. Anderson, a citizen of the United States and residing in the city of Weehawken, county of Hudson, and State of New Jersey, have invented a new, original, and ornamental Design for Symbol Template, of which the following is a specification, reference being had to the accompanying drawing, forming a part thereof.

Fig. 1 is a top plan view of a symbol template, showing my new design; and

Fig. 2 is an end elevational view thereof.

The bottom of the template has a long straight line generally similar to the one on the front but in the relative position as illustrated by the grooves in Fig. 2.

I claim:

The ornamental design for a symbol template, as shown and described.

ROBERT W. ANDERSON.
